A. GRIMM

TERMINAL FOR AUTO INTERNAL FORGING OF TUBES

Filed Jan. 10, 1919

Fig. 1.

Fig. 2.

Fig. 3.

INVENTOR:

Arthur Grimm

UNITED STATES PATENT OFFICE.

ARTHUR GRIMM, OF NEW YORK, N. Y., ASSIGNOR TO KAS-SO KITCH-E-MON-E-TOO SO-NE-AH LIMITED, OF MONTREAL, QUEBEC, CANADA, A CORPORATION OF CANADA.

TERMINAL FOR AUTO INTERNAL FORGING OF TUBES.

Application filed January 10, 1919. Serial No. 270,601.

To all whom it may concern:

Be it known that I, ARTHUR GRIMM, doctor of dental surgery, a citizen of the United States, residing at New York city, in the county and State of New York, have invented new and useful Improvements in Terminals for Auto Internal Forging of Tubes, of which the following is a specification.

10

Tube.

By the term "tube", I mean any tube or hollow metal body of any shape or form; such a tube or hollow metal body may be made in one piece, or may be made of two or more tubes one in the other thus forming a compound tube; such a tube may be of any metal or alloy, of elastic properties, or may be made up of several metals or alloys, of elastic properties; such a tube may be of any size or sizes, and for any purpose whatsoever.

Auto-internal-forging.

By the term "auto-internal-forging", I mean that art of tube manufacture by which a tube is stretched cold or hot by means of forcing into said tube fluid under sufficient pressure to so stretch the wall or walls of said tube, even to the point of rupture if need be.

Terminal.

By the term "terminal", I mean the device, valve or cork that is inserted at the opening, or, if need be, at openings of the tube, to hold in the fluid that is forced in and that is to stretch the rings or grippers of the said terminal with the wall or walls of said tube between said terminals.

40

Fluid.

By the term "fluid", I mean air, gas, water, alcohol, oil, or any other substance suitable for the purpose.

45 My invention relates to a tube and its terminal or device that is so constructed that once placed in said tube, which is closed at other end either by another terminal or by other means, will allow fluid to be forced in the tube with such pressure as to stretch the rings or grippers of the terminal or terminals with the wall or walls of said tube,

even to the point of rupture if need be. The greater the pressure inside the tube behind the terminal the harder said terminal or terminals will hold in place due to the greater expansion of the walls of said terminal or terminals with the wall or walls of said tube at those points.

The application of my invention will be better understood by referring to the drawings:

Figure One is a cross-section on line CD of Figure Two, showing a terminal at one end of a tube that is closed at other end either by a second terminal, or by other means (Fig. 1).

Figure Two is a cross-section on line AB of Figure One.

Figure Three is a half cross-section on line CD of Figure Two.

In a tube 1 (Figs. 1 and 2) that is to be auto-internal-forged, is placed the terminal 2 (Figs. 1, 2 and 3) made very much like a common wooden spool for thread, the space for the thread being filled by a slide ring or gripper 3 (Figs. 1 and 2), or several slide rings, one encasing the other, or one in front of the other, the whole forming a multiple slide ring or gripper 3 (Figs. 1 and 2), which slide ring or rings are solid or split as shown in Figure Two, and which allow a space 4 (Figs. 1, 2 and 3) between said ring or rings, or gripper or grippers 3 (Figs. 1, 2 and 3) and body of terminal proper 2 (Figs. 1, 2 and 3).

Where exceedingly high pressures are to be retained in space 8 and space 4 (Figs. 1, 2 and 3), the terminal 2 (Figs. 1, 2 and 3) may be a multiple terminal having several integral peripheral flanges, and grippers; or in other words two or more terminals one behind the other (in tandem), of which part 2 (Figs. 1, 2 and 3) is one member for all.

From body of terminal proper 2 (Figs. 1, 2 and 3) at its outer end protrudes a small boss 5 (Figs. 1 and 3) that is connected to supply pressure pipe by threads, as shown, or that may be closed by a suitable cap or stopper; and, at center of this boss 5 (Figs. 1 and 3) is a hole 6 (Figs. 1, 2 and 3) that connects at its inner end to space 8 (Fig. 1) of tube that is to be filled with space 4 (Figs. 1, 2 and 3) under pressure by

fluid. As the fluid enters space 8 (Fig. 1) of tube through hole 6 (Figs. 1, 2 and 3) and rises in pressure, it enters another hole 7 (Figs. 1, 2 and 3) and fills up space 4 (Figs. 1, 2 and 3) with a pressure equal to that in space 8 (Fig. 1) thus forcing out slide ring or rings, or gripper or grippers, 3 (Figs. 1, 2 and 3) against the tube, which ring or rings, or gripper or grippers 3 10 (Figs. 1, 2 and 3) thus become homogeneous with the wall or walls of the said tube 1 (Figs. 1 and 2), and thus prevent the fluid and the terminal or device to slide out.

Terminal 2 (Figs. 1, 2 and 3) may or 15 may not have a nose or rod 9 (Fig. 1), extending into space 8 (Fig. 1) so as to reduce the amount of fluid that is to fill space 8 (Fig. 1). Said rod 9 (Fig. 1) may be cut up in several pieces forming a row of small 20 rods one in front of the other for facility of handling. Said rod 9 (Fig. 1) may or may not be terminals if such are used.

When pressure in space 8 (Fig. 1) is released, pressure in space 4 (Figs. 1, 2 and 25 3) is also released thus allowing slide ring or rings, or gripper or grippers, 3 (Figs. 1, 2 and 3) to spring back and terminal or device to be easily removed if so desired or placed at some other point in tube.

30 Tube or tubes, or hollow metal bodies, auto-internal-forged with said terminal are and can be used for medical, surgical, dental, commercial and ordnance purposes.

Although I have shown one specific design for terminals and their tubes, in their simultaneous process of auto-internal-forging, in the figures, yet I wish it understood that I do not restrict myself thereby to any specific dimensions or details.

40 Tubes or hollow metal bodies and their terminal or terminals, auto-internal-forged, come under one of those instances where an article or object as a whole is defined by the method of making it, it being almost impossible to satisfactorily define it in any other way. It is for the above reason that, having described my invention in annexed 45 specifications, I set forth my claims in terms of the structure itself as a whole, and, in

terms of the method practised in producing 50 that structure.

The claims are intended to cover and do cover only the same subject matter of my invention of terminals and their tubes simultaneously auto-internal-forged, which I claim 55 as new and desire to secure by Letters Patent, viz:

1. A device for auto-internal-forging by fluid pressure, consisting of a terminal and its gripper on its recessed peripheral surface, said terminal being adapted to fit closely within its tube, and being provided with means whereby fluid pressure may be passed through the terminal from the outer to the inner end thereof, and also with 60 means whereby said fluid pressure may be passed from said inner end to said gripper to operate it to grip and become an homogeneous part of the wall of the tube to secure the whole in position. 70

2. A device for auto-internal-forging by fluid pressure, consisting of a terminal and its grippers (in tandem) on its recessed peripheral surface, said terminal being adapted to fit closely within its tube, and being provided with means whereby fluid pressure may be passed through the terminal from the outer to the inner end thereof, and also with means whereby said fluid pressure may be passed from said inner end to said 75 grippers to operate them to grip and become homogeneous parts of the wall of the tube to secure the whole in position.

3. A device for auto-internal-forging by fluid pressure, consisting of a terminal and 80 its grippers (in tandem) on its several recessed peripheral surfaces, said terminal being adapted to fit closely within its tube, and being provided with means whereby fluid pressure may be passed through the 85 terminal from the outer to the inner end thereof, and also with means whereby said fluid pressure may be passed from said inner end to said grippers to operate them to grip and become homogeneous parts of the 90 wall of the tube to secure the whole in position. 95

ARTHUR GRIMM.
